CLAIM

The ornamental design for a furniture item, as shown and described.

DESCRIPTION

FIG. 1 is a bottom, front, right perspective view of the claimed design for a furniture item;

FIG. 2 is an enlarged fragmentary view of FIG. 1;

FIG. 3 is an enlarged fragmentary bottom, front, right perspective view of the claimed design in an alternative configuration;

FIG. 4 is an enlarged, fragmentary view of FIG. 3, wherein only the foot is shown;

FIG. 5 is a top, front, right perspective view of the claimed design for a furniture item;

FIG. 6 is a second top, front, right perspective view thereof;

FIG. 7 is a front view thereof;

FIG. 8 is a rear view thereof;

FIG. 9 is a left side view thereof;

FIG. 10 is a right side view thereof;

FIG. 11 is a top view thereof; and,

FIG. 12 is a bottom view thereof.

The uneven-length broken lines in FIGS. 2-3 are for the purpose of framing the enlarged, fragmentary views and form no part of the claimed design. The even-length broken lines immediately adjacent to the shaded area are for the purpose of illustrating portions of the article and form no part thereof. The even-length broken lines showing the remainder of the furniture item depict environmental structure and form no part of the claimed design. The unshaded regions within the shaded area that are demarcated by even-length broken lines form no part of the claimed design. Portions of the furniture item not shown in the drawing form no part of the claimed design.
